UNITED STATES PATENT OFFICE.

ANDREW KOESCHE, OF CHICAGO, ILLINOIS.

ELECTRIC PUMP-REGULATOR.

No. 881,247.

Specification of Letters Patent. Patented March 10, 1908.

Application filed September 13, 1907. Serial No. 392,621.

To all whom it may concern:

Be it known that I, ANDREW KOESCHE, a citizen of the United States, residing at Chicago, in the county of Cook and State of Illinois, have invented new and useful Improvements in Electric Pump-Regulators, of which the following is a specification.

The object of this invention is to provide an electric pump regulator of inexpensive construction and simple operation to automatically start and stop a pump as required, for example to maintain a predetermined volume of water in a tank.

In the accompanying drawings I have illustrated the invention as adapted for connection with a closed water tank to be operated by pressure in the tank.

Figure 1 is a plan view, partly in section, showing the parts in closed position in full lines and in open position in broken lines. Fig. 2 is a sectional view on the line 2—2 of Fig. 1. Fig. 3 is a sectional view on the line 3—3 of Fig. 1.

In the adaptation of the invention shown in the drawings, a cylinder 4 is mounted on a suitable insulating base 5 and connected by a pipe 6 with a closed water tank. A piston 7 is carried by a stem 8 within the cylinder 4 and this stem is guided in a bracket 9 on the base and has its upper end provided with an eye 10. A lever 11 passes through the eye 10 and is fulcrumed at one end 12 on the base and carries a weight 13 at its other end.

I have shown a double pole switch in which there are two stationary contacts 14 mounted on the base and two movable contacts 15, the former being in the familiar form of spring contacts and the latter in the form of blades to engage the spring contacts. The stationary contacts 14 are connected by wires 14' with binding posts 16 to which the line wires 16' are connected. The movable contact blades 15 are on levers 17 fulcrumed at 17' on the base and connected at their fulcrums by wires 15' with binding posts 18 to which the motor wires 18' are connected.

Angle levers 19 are fulcrumed at 20 on the bracket 9 and have arms 19', 19''. The arms 19' carry fiber blocks 21 and springs 22 are connected to posts 23 on said blocks and posts 24 on the levers 17. The arms 19'' are engaged by a tripper on the stem 8, this tripper comprising a bracket 25 fastened in adjustable position on the stem and two pairs of fingers 26 spaced apart and adjustably fastened in sockets 26' in the bracket (Fig. 3).

The free end of each arm 19'' projects into and operates freely in the space between each pair of fingers 26. Each of the fiber blocks 21 is provided with a projection 21' which is arranged to engage a lug 27 on the underside of the movable contact lever 17 (Fig. 2) and cushioned stops 28 are located on the base to limit the movement in one direction of the movable contacts.

In practice the center of the fulcrum of each angle lever is located out of alignment with the center of the fulcrum of its movable contact lever and preferably in a line between the center of the fulcrum of the movable contact lever and the stationary contact. The fingers 26 are adjusted so that the two switches will be operated simultaneously and at the proper time. When the pressure on the piston overcomes the weight on the lever 11 and forces the piston up in the cylinder the tripper will be carried upward to swing the angle levers on their fulcrums. When the posts 23 are moved inward past the center line of the fulcrums 17' the springs 22 will swing the levers 17 against the stops 28 thereby breaking the contacts as indicated in broken lines in Fig. 1. If for any reason the springs fail to swing the levers 17 at the proper time the projections 21' will engage the lugs 27 and swing said levers to break the contacts. When the pressure under the piston diminishes and the weight 13 causes the piston to descend the tripper will swing the angle levers in the opposite direction and cause the levers 17 to swing from the position indicated in broken lines in Fig. 1 to the position shown in full lines.

The invention is simple in construction and accurate in its operation. The parts can be readily adjusted to effect the operation of the switches at any desired pressure and to insure the simultaneous operation of the switches. While I have stated that the pipe 6 is connected to a tank it is obvious that the regulator can be otherwise applied and operated by air, gas, steam or water with equally satisfactory results. It will be observed that the contacts are widely and quickly separated when broken by a gap of sufficient width to prevent sparking and flashing under high voltage.

While I have shown and described a piston for moving the tripper, in the particular adaptation of the invention herein referred to, I do not limit myself to this particular means for operating the tripper for obviously

it can be actuated by other means in substantially the same manner and with equivalent results.

What I claim and desire to secure by Letters Patent is:

1. The combination of a movable tripper, an electric switch comprising a stationary contact and a movable contact, a two arm angle lever having one arm engaged with the 10 tripper, a lever pivoted independently of said angle lever and carrying said movable contact and extending in the same general direction from its pivot as the other arm of said angle lever and in the several positions 15 thereof, the fulcrum center of said angle lever being located out of line with the fulcrum center of the contact lever and the stationary contact, and a spring connected to said other arm of the angle lever and to said 20 contact lever.
2. The combination of a movable tripper, an electric switch comprising a stationary contact and a movable contact, a lever carrying said movable contact, a two arm angle 25 lever having one arm engaged with the tripper, a spring connected to the other arm of the angle lever and to the movable contact lever, a lug on said movable contact lever, and a projection on the angle lever to 30 engage said lug.
3. The combination of an electric switch comprising a stationary contact and a mov-

able contact, a lever carrying said movable contact, a two arm angle lever pivotally mounted independent of said contact lever, the fulcrum center of said angle lever being 35 out of line with the fulcrum center of the contact lever and the stationary contact, a spring connected to said contact lever and to one arm of said angle lever, and a movable tripper for operating said angle lever and comprising a pair of fingers between which the other arm of the angle lever projects, said fingers being independently adjustable longitudinally to regulate the movement of 40 45 said angle lever.

4. The combination of a pressure cylinder, a piston in said cylinder, a stem carrying said piston, a weighted lever engaged with the stem, a tripper comprising a bracket on the stem, a pair of arms spaced apart and projecting from the bracket on each side thereof, a pair of electric switches each comprising a stationary contact and a movable contact, a lever carrying the movable contact, a pair of 50 two arm angle levers each having one arm projecting into the space between a pair of fingers, and springs connected to the movable contact levers and to the other arms of the angle levers.

ANDREW KOESCHE.
